UNITED STATES PATENT OFFICE.

GEORGE P. TILTON, OF NEWBURYPORT, MASSACHUSETTS, ASSIGNOR TO
TOWLE MANUFACTURING COMPANY, OF NEWBURYPORT, MASSACHU-
SETTS, A CORPORATION OF MASSACHUSETTS.

DESIGN FOR A HANDLE FOR SPOONS, FORKS, OR SIMILAR ARTICLES.

SPECIFICATION forming part of Design No. 36,879, dated April 19, 1904.

Application filed July 17, 1902. Serial No. 116,009. Term of patent 14 years.

To all whom it may concern:

Be it known that I, GEORGE P. TILTON, a citizen of the United States, residing at Newburyport, in the county of Essex and State 5 of Massachusetts, have invented a new, original, and ornamental Design for a Handle for Spoons, Forks, or Similar Articles, of which the following is a specification, reference being made to the accompanying drawings, forming a part thereof.

Figure 1 is a front plan view of a spoon,

showing my design. Fig. 2 is a back or obverse plan view of a spoon, showing my design.

What I claim as new, and desire to secure 15 by Letters Patent, is—

The ornamental design for the handle of a spoon, fork, or similar article, as shown.

GEORGE P. TILTON.
